UNITED STATES PATENT OFFICE.

LA GEE TABER, OF MERIDEN, CONNECTICUT.

BURNISHING KNIFE-BLADES.

SPECIFICATION forming part of Letters Patent No. 241,750, dated May 17, 1881.

Application filed March 14, 1881. (No model.)

To all whom it may concern:

Be it known that I, LA GEE TABER, of Meriden, in the county of New Haven and State of Connecticut, have invented a new Improvement in Burnishing Knife-Blades; and I do hereby declare the following, when taken in connection with the accompanying drawings and the letters of reference marked thereon, to be a full, clear, and exact description of the same, and which said drawings constitute part of this specification, and represent, in—

Figure 1, a top or plan view; Fig. 2, a front-end view.

This invention relates to an apparatus for burnishing the blades of plated table-knives.

Various devices have been made for doing this work by performing it first upon one side of the blade and then upon the other; but up to this time no practical apparatus has been devised to successfully do this work.

My invention, which, from actual test, has proved itself capable of burnishing the blades in the most perfect manner, consists in the construction as hereinafter described, and particularly recited in the claims.

A represents a cross-head with a shank, B, arranged to set into a reciprocating spindle or slide, C, of a burnishing-machine, or may be attached to any device which will impart to it a reciprocating movement. At each side of the center of the cross-head arms D and D' are hinged, as at a. The outer end of these arms are fitted with a burnishing-roll, d, such as commonly used, and made from hard finely-polished steel or from other suitable material, and should be in the shape of wheels hung upon an axis substantially parallel with the path of movement of the burnisher-arms, and as shown the two burnishers are in the same transverse line—that is, in the same plane. The blade E of the knife is placed between the burnishers and substantially parallel with their path of movement, the handle F firmly secured in a holder, G, and so that one burnisher will lie upon one side of the blade and the other upon the opposite side, as shown, and so that as the burnishers are moved along the sides of the blade from bolster to point they burnish the surface over which they pass, and as they pass back and forth from bolster to point either the blade is moved slowly up or down or the

burnishers are so moved—that is to say, so that, beginning at the back of the blade, the burnishers will gradually work toward the edge until they pass from it, leaving the blade completely and perfectly burnished. 55

As here represented, the holder for the knife is arranged to move up and down by means of a hand-screw, L, in connection with the holder G, the said holder being arranged between guides H H, as shown.

Any convenient device may be arranged for clamping the handle in the holder, as by a set-screw, e, or otherwise, arranged, however, with some protection between it and the handle to prevent the clamping from injuring the handle. 65

It will be understood that other means may be employed to cause the burnishers, during their reciprocation on the opposite sides of the blade, to gradually work from one edge of the blade to the other. 70

To make an elastic pressure of the burnishers upon the blade and equal upon both sides, I hang an arm, P, at each side, as upon a pivot, f, the outer end of the said arms bearing 75 against a cheek-piece, R, and preferably with an interposed anti-friction roll, I, as shown; then, between the burnisher-arms and the arms P, I introduce a spring-pressure, here represented as by a spiral spring, s. 80

The cheek-pieces R may be adjustable, so as to correspond to the taper of the blade or to make a greater or less pressure.

Instead of applying the spring-pressure through the arms P, pressure may be applied 85 by, say a flat spring extending from the cross-head, as indicated in broken lines on the right-hand side, it only being essential that there shall be a corresponding or substantially equal pressure upon both the burnisher-arms. 90

To prevent the two burnishers from coming into actual contact, a stop, h, is arranged on the cross-head, near the pivot, and a shoulder, n, on each of the hubs of the levers, which will strike their respective stops and prevent their 95 coming in contact. These stops are best made in the form of screws, as shown, so as to be adjustable, because in changing the burnishers different diameters may be employed. Then such adjustment would be essential, as the 100 burnishers must come so near together that they will burnish the blades down to the sharp

edge, and yet should not be so as to come into actual forced contact.

I claim—

1. The combination of two hinged burnisher-
5 arms, each provided with its burnisher, means,
substantially such as described, to impart a
reciprocating movement thereto, with a holder
constructed to hold the blade between said
burnishers and in the line of movement of
10 said burnishers, mechanism, substantially such
as described, to impart to the holder a move-
ment, substantially as described, in relation to
the reciprocating burnishers, so that during the
reciprocating movement of the burnishers the
15 knife-blade is gradually burnished from one
edge to the other, substantially as described.
2. The combination of two hinged burnisher-
arms, each provided with its burnisher, mech-
anism, substantially such as described, to im-
20 part a reciprocating movement thereto, with a
holder constructed to hold the blade between
said burnishers and in the line of movement
of said burnishers, mechanism, substantially
such as described, to impart to holder a move-
25 ment substantially as described in relation to
the reciprocating burnishers, so that during

the reciprocating movement of the burnishers
the knife-blade is gradually burnished from
one edge to the other, and adjustable stops to
prevent contact of the burnishers, substantially 30
as described.

3. The combination of two hinged burnisher-
arms, each provided with its burnisher, mech-
anism, substantially such as described, to im-
35 part a reciprocating movement thereto, with a
holder constructed to hold the blade between
said burnishers and in the line of movement
of said burnishers, and mechanism, substan-
tially such as described, to impart to the holder
40 a movement substantially as described in re-
lation to the reciprocating burnishers, so that
during the reciprocating movement of the bur-
nishers the knife-blade is gradually burnished
from one edge to the other, with mechanism,
45 substantially such as described, to impart a
forced yielding pressure to the burnishers, sub-
stantially as described.
